ABSTRACT OF THE DISCLOSURE

Process for treating a cellulosic digesting liquor containing soap with a liquid hydrocarbon and alcohol to separate the soap from the liquor.

BACKGROUND OF THE INVENTION

In the past, cellulosic digesting liquor, which is the used cooking liquor from pulp digesters, has been concentrated by various evaporating techniques. In a typical case this digesting liquor is the used black cooking liquor from kraft digesters. Kraft digesters are employed to process wood pulp. This black liquor contains many valuable by-products which are commonly separated from the used cooking liquor by a multiple evaporation procedure.

Among the valuable components of black liquor are various tall-oil soaps. Heretofore, such soap has been separated from the black liquor by feeding concentrated liquor, also known as skimmer feed, into a skimming tank. The liquor is retained in the skimming tank until the entrained tall-oil soap floats to the surface of the liquor, where it may be removed by skimming. The skimmed soap is the raw material for conventional tall-oil processing.

The black liquor is discharged from the bottom of the skimming tank afterwards and fed to the next evaporator effect. Black liquor is at this point commonly known as skimmer discharge. This liquor contains about 25% of the soap which was present in the skimmer feed. Therefore the soap recovery efficiency of present methods is about 75%. Generally, the remaining soap in the skimmer discharge is lost to the process.

In an effort to increase the quantity of soap recovered from skimmer feed, it has been proposed to inject a solvent, usually a liquid hydrocarbon, into the skimmer feed, prior to conventional skimming. The solvent floculates the entrained soap in skimmer feed such that a soap-solvent layer rises to the top of the skimmer tank and is recovered. The recovered soap solvent layer is processed in order to remove solvent and recover soap. The skimmer discharge, containing residual soap and solvent, is fed to the next evaporator effect where the solvent is distilled and separated from the black liquor.

This process has several major drawbacks. Solvent recovery from the skimmer discharge has proven highly unsatisfactory. This low solvent recovery is due, in part, to the greater miscibility of the typical hydrocarbon solvent in black liquor than would have been expected. Also, there appears to be a definite limit as to the quantity of soap which may be recovered from the skimmer feed by this process. This limit is determined, in part, by the quantity of soap which is dissolved in the skimmer feed, as opposed to the soap present in skimmer feed as discrete soap particles. The hydrocarbon solvent is relatively ineffective in extracting dissolved soap from black liquor, and acts generally as a coagulating agent for soap particles.

2**SUMMARY OF THE INVENTION**

It is, therefore, a principal object of this invention to provide a process for removing soap from a cellulosic digesting liquor employing a solvent which is readily recovered from said liquor, for recycling to the process. It is another object of this invention to provide a process for recovering both dissolved soap and soap particles from black liquor. It is an additional object of this invention to provide a soap removal process which is readily integrated with conventional black liquor concentrating processes.

Other aspects, objects and advantages of this invention will be evident as the discussion proceeds.

The above and other objects of this invention are achieved by treating a cellulosic digesting liquor containing soap with a liquid hydrocarbon and an alcohol. The liquid hydrocarbon and alcohol (hereinafter referred to as mixed solvent) collect the soap in a phase or layer at the surface of the black liquor. This layer, containing, in part, soap, liquid hydrocarbon, alcohol, and water is removed from the black liquor and may be treated so as to recover the hydrocarbon and alcohol for recycle purposes.

De-soaped black liquor containing residual mixed solvent is recycled to conventional black liquor concentrating processes. Mixed solvent is recovered from the concentrating process by conventional techniques and recycled for further use.

The novel process is employed, for example, to extract tall oil soap from the sulfate black liquor employed as the cooking liquor in kraft digesters. As black liquor is concentrated by evaporation in multiple-effect evaporator, the concentration of soap in the liquor increases. When the black liquor concentration is from about 22 to 26% by weight solids based on total weight of liquor, the solubility of the entrained soap reaches a minimum. At this point in the concentrating process, the black liquor (skimmer feed) flows into a conventional skimming tank and is retained therein for about an hour. During this period, soap floats to the surface to be skimmed. After skimming, the black liquor is discharged from the bottom of the skimming tank. At this point the black liquor is commonly known as skimmer discharge.

Additional tall oil soap is processed from said skimmer discharge by mixing the skimmer discharge with the mixed solvent and then introducing this mixture into a holding tank. Upon standing, a layer comprising soap, water, and mixed solvent separates and rises to the surface of the tank.

This layer may be separated from the black liquor remaining by conventional separation techniques, such as skimming, decanting, pumping, or the like. Mixed solvent is separated from the soap by conventional techniques. If desired, the mixed solvent may be evaporated from the soap by steam stripping, flash drying, vacuum distillation, or the like. The recovered mixed solvent is recycled to treat additional skimmer discharge.

The black liquor remaining in the holding tank after the soap layer has been removed is discharged from the holding tank and may be introduced into an appropriate stage of the multi-effect evaporator. This discharged liquor contains minute amounts of residual mixed solvent. This solvent is readily recovered from the liquor in the multiple-effect evaporator.

The liquid hydrocarbon constituent of the mixed solvent is aliphatic or aromatic. The hydrocarbon may be saturated or unsaturated. Typical examples of hydrocarbons employed are: alkanes, alkenes, arylalkanes, cycloalkanes, cycloalkenes, and mixtures thereof. Generally

the liquid hydrocarbon employed has a boiling point in the range of from about 100 to 200° C.

Examples of specific hydrocarbons includes heptane, octane, decane, 2-ethyl heptane, dodecane, pentane, cyclooctane, cyclohexane, cyclohexene, norcarane, cis or trans Decalin, diethylbenzene, cyclohexylbenzene, and the like, and mixtures thereof.

Generally the alcohol employed in the process can be aliphatic or aromatic. The alcohol may be saturated or unsaturated. Examples of typical alcohols include alkanols, alkenols, alicyclic alcohols, alkaryl alcohols, aralkyl alcohols and the like.

Specific examples of alcohols employed in the process include: methanol, ethanol, isopropanol, cyclopentanol, 2-ethyl - 1 - butanol, tert-amyl alcohol, benzyl alcohol, allyl alcohol, methylcyclohexanol, furfuryl alcohol, ethyl-phenylcarbinol, methylphenylcarbinol, cyclohexylcarbinol, metatolylcarbinol, and the like.

Alcohols having functional groups are also employed. Examples of such alcohols are: 2-bromo-ethanol, 2-3-dichloro-1-propanol, and the like. Generally, the functional groups on said alcohol must not react with any constituent in the black liquor.

The choice of alcohol for a particular system depends, in part, on the quantity of water in the black liquor, the temperature of the black liquor, the chemical composition of the black liquor, and also the choice of hydrocarbon. Usually, the alcohol should be of sufficiently high volatility as to be readily separable from the soap layer by evaporating techniques. Generally alcohols with high water solubility are not employed in order to reduce solvent loss.

Typical mixtures of alcohol and hydrocarbon include the following:

- (1) Propenylbenzene, cyclopentanol
- (2) Undecane, 4-methyl-2-pentanol
- (3) Benzene, 2-phenyl-1-heptanol
- (4) 1, 3, 5-triethylbenzene, benzyl alcohol

Other mixtures are formed by combining any alcohol listed above with any hydrocarbon listed above.

By employing the aforementioned process, it has been found that certain advantages are achieved. The quantity of residual mixed solvent discharged with black liquor into the multiple-effect evaporator is significantly reduced, as compared to prior art desoaping processes. Further, the quantity of mixed solvent lost to the black liquor, after evaporation or the like, is less than one tenth of the quantity of hydrocarbon solvent lost by previous processes. Further, soap extraction is improved, owing to the enhanced solubility of entrained soap in mixed solvent.

DETAILED DESCRIPTION OF PREFERRED EMBODIMENTS

Generally, enhanced soap recovery is achieved and reduced solvent loss is observed, when the novel process is employed in conjunction with a conventional skimmer feed skimming process. The mixed solvent of the invention is preferably added to skimmer discharge to recover incremental tall oil soap, after conventional skimming.

The process is preferably employed by premixing the alcohol and hydrocarbon and thereafter adding the premixed solvent to skimmer discharge. The mixed solvent-skimmer discharge mixture is preferably agitated with aeration to free entrained soap particles. After thorough mixing, the mixture is preferably transferred to a holding tank. In the holding tank a soap phase forms at the top of the mixture. Generally, the soap phase is sufficiently formed so as to be easily removed after at least about 30 minutes of settling. For maximum soap recovery it is preferred to settle the contents in the holding tank for from about one to two hours.

It is preferred to employ a covered holding tank in order to minimize solvent loss. The soap phase in the

holding tank is skimmed from the surface of the black liquor and transferred to a mixed solvent removal stage, preferably a steam stripper. The entire process is suitably employed on a continuous or semi-continuous basis, although it may be performed on a batch-wise basis.

The hydrocarbon is preferably immiscible with black liquor to reduce solubility losses. Preferred hydrocarbons include aromatic hydrocarbons or mixtures of aromatic hydrocarbons. Enhanced results are obtained by aromatics having an initial boiling point in the range of from about 300 to 400° F. and flash points of at least about 100° F. Commercial aromatic mixtures boiling in this range which are especially preferred include Solvesso 100, Solvesso 150, and Neville 250W. Xylene is an excellent hydrocarbon for the purposes of this invention. Examples of other preferred aromatic hydrocarbons include, for instance: toluene, ethylbenzene, xylene, isopropylbenzene, and mixtures thereof.

Preferred hydrocarbons also include petroleum solvents boiling in the naphtha range. Examples of still further preferred hydrocarbons are cycloalkenes; including pinene, camphene, bornylene, carene, and other turpentine constituents. Sulfate turpentine which may be crude or distilled and comprises primarily cycloalkenes, is also employed.

Monohydric alcohols are preferred, especially alkanols. Particularly preferred alcohols are those alkanols having from about 8 to about 12 carbon atoms. Such alcohols include: octyl alcohol, nonyl alcohol, undecyl alcohol, decyl alcohol, and dodecyl alcohol.

The alcohol is preferably immiscible with black liquor and insoluble in water to reduce solubility losses. A most preferred alcohol is decyl alcohol.

Typical examples of preferred mixed solvents include:

- 35 (1) Xylene; methylnonyl alcohol;
- (2) Solvesso 150 (an aromatic hydrocarbon solvent flash point 150° F., and derived from petroleum); decyl alcohol;
- 40 (3) Sulfate turpentine (a mixture of cycloaliphatics, predominantly pinene and derived from wood pulp); decyl alcohol;
- (4) Solvesso 100 (an aromatic hydrocarbon solvent flash point 100° F. and derived from petroleum); isodecyl alcohol;
- 45 (5) Pinene, n-decyl alcohol;
- (6) Ethylbenzene, isononyl alcohol;
- (7) Toluene, n-undecyl alcohol;
- (8) Isopropyl benzene, n-dodecyl alcohol;
- 50 (9) Benzene-toluene mixture, decyl alcohol;
- (10) Sulfate turpentine (distilled) isodecyl alcohol.

Generally, the proportions of alcohol to hydrocarbon may vary broadly. It is preferred that the proportion of alcohol, particularly monohydric alkanols, having from about 8 to 12 carbon atoms, is from about 5 to 75% by weight of the total mixed solvent and the proportion of hydrocarbon, particularly aromatic hydrocarbon having an initial boiling point in the range of from about 300° to about 400° F. is from about 95% to 25% by weight of the total mixed solvent.

Enhanced results are obtained and accordingly, it is preferred to employ the mixed solvent in the following proportions: 10% to 50% by weight alcohol and 90% to 50% by weight hydrocarbon, based on the total weight of alcohol and hydrocarbon.

If desired, to aid in the extraction of soap, conventional electrolytes may also be employed. These are added to the skim feed or the skim discharge.

The following examples are illustrative only.

EXAMPLE I

In order to demonstrate the effect of the novel process on soap recovery, conventionally skimmed back liquor was treated with mixtures of Solvesso 150 and n-decyl alcohol. Solvesso 150 is a proprietary mixture of aromatic solvents

derived from petroleum having an initial boiling point of about 360° F. and a flash point of 150° F.

A metered amount of skinned discharge containing 0.6% by weight tall oil on solids and a metered amount of mixed solvent were mixed in a Venturi tube. The mixture was introduced into a mixing vessel, said vessel being mounted in a settling tank. The mixture was stirred and aerated therein. After about five minutes of stirring, the mixture overflowed to the settling tank, where it was accumulated. An outlet valve on the bottom of the settling tank was opened, such that the level of material in the settling tank remained constant. After an hour, samples were taken from the black liquor discharge. A second set of samples was taken at a higher mixed solvent rate. The samples were analyzed for residual tall-oil in the black liquor phase.

The residual tall-oil in the black liquor was analyzed by Mill Technical Division Method A.M. 265, commonly known as the "Buckeye Method" as described in TAPPI, vol. 42, 1959. The concentrations of tall-oil in the table below are given as the weight percent tall-oil based on total liquor solids. In the table below, the proportion of alcohol is given in weight percent of the total mixed solvent. The solvent flow rate is expressed in volume percent of mixed solvent per volume of black liquor.

RESIDUAL TALL-OIL ANALYSES

Weight percent decyl alcohol in mixed solvent	Residual tall-oil on solids	
	1% solvent flow rate	2% solvent flow rate
10-----	0.41	0.32
50-----	0.30	0.24

The results demonstrate that the mixed solvent comprising an alcohol and liquid hydrocarbon, effectively extracts soap from cellulosic digesting fluid, particularly kraft black liquor. The level of tall-oil on black liquor solids initially present in the skimmer discharge prior to treatment was 0.60 weight percent tall-oil on solids. A marked increase in tall-oil recovered is shown by the addition of mixed solvent to skimmer discharged.

When other liquid hydrocarbons and alcohols are substituted for the mixed solvent employed in the previous test, similar results are obtained. Other mixed solvents which may be substituted for the above include:

- (1) Nonyl alcohol, xylene
- (2) Undecyl alcohol, turpentine
- (3) Ethylene glycol monomethyl ether, toluene and mixtures thereof.

EXAMPLE II

In order to demonstrate the efficiency with which the mixed solvent is recovered from both the black liquor and soap phases, black liquor was treated according to the procedure of Example I, employing a mixed solvent, n-decyl alcohol and Solvesso 150, and soap skimmed therefrom. The treated black liquor discharge was then concentrated by evaporation from its initial solids content of about 25% to a final content of 29% solids.

The skinned soap phase was steam-stripped to recover solvent. The mixed solvent recovered from both the discharged black liquor and the steam-stripper was individually analyzed. To provide comparative results, a run was performed according to the above procedure employing solely a hydrocarbon solvent. The following table shows the results obtained.

The treated skimmer discharge columns show the quantity of mixed solvent in parts per million present in black liquor recycled to the multiple-effect evaporators after soap extraction with mixed solvent. The total mixed solvent loss represents the mixed solvent lost to black liquor which has been treated to evaporate mixed solvent, and the mixed solvent lost to the soap phase recovered from the steam-stripper. The solvent flow rate and percent decyl alcohol columns were reported as in Example I.

SOLVENT ANALYSES

Mixed solvent, percent by weight decyl alcohol	Solvent flow rate in volume percent	Treated skimmer discharge		Total mixed solvent loss in p.p.m.
		Hydrocarbon in p.p.m.	Alcohol in p.p.m.	
0-----	1	1,494	0	335
10-----	1	553	141	87
10-----	2	417	159	71
50-----	1	152	406	92
50-----	2	168	507	89
100-----	2	0	1,350	141

The results demonstrate the reduced solvent loss of the mixed solvent as compared to a simple hydrocarbon solvent. The results also demonstrate the enhanced separation of the novel solvent from the black liquor skimmer discharge which is treated in the holding tank to remove additional tall-oil soap. Similar results are obtained when other mixed solvents are substituted for the above solvent mixture.

The additional (incremental) soap recovered by the novel process was compared with normal skim soaps, as presently obtained during conventional skimming procedures, without employing solvents. The incremental soap showed a greater than 50% reduction in unsaponifiable matter as compared to normal skim soap. Other advantages are obtained by the invention. Whereas conventional skimming without solvents generally causes an undesirable, hard to process, stable foam to be produced at the surface of the black liquor, it has been found that an easily processable thick skim is produced by the action of the mixed solvent.

We claim:

1. A process for treating a cellulosic digesting liquor containing soap comprising admixing said liquor and a mixed solvent comprising a mixture of from about 90 to 50% by weight petroleum aromatic hydrocarbons having an initial boiling point in the range of from about 300-400° F. and a flash point of at least about 100° F. and from about 10 to 50% by weight decyl alcohol, wherein said weights are based on the total weight of the mixed solvent, whereby a soap-containing phase is formed at the surface of the mixture which may be removed and soap recovered therefrom.
2. A process for treating kraft black liquor skimmer discharge containing tall-oil soap comprising:
  - (a) forming a liquid mixed solvent comprising a mixture of from about 90 to 50% by weight petroleum aromatic hydrocarbons having an initial boiling point in the range of from about 300-400° F. and a flash point of at least about 100° F. and from about 10 to 50% by weight decyl alcohol, wherein said weights are based on the total weight of the mixed solvent;
  - (b) mixing said solvent and said skimmer discharge;
  - (c) introducing said mixture into a holding tank, wherein a layer comprising soap and mixed solvent is formed;
  - (d) separating said layer from the black liquor; and
  - (e) recovering soap from said layer.
3. In the process for concentrating black liquor containing soap from kraft digesters by the stepwise evaporation of volatile components therefrom, wherein a portion of the soap is separated from said black liquor by settling said liquor, skimming off a soap layer formed on the surface of said liquor and recycling the remaining black liquor skimmer discharge to the concentrating process, the improvement by means of which additional soap is separated from the skimmer discharge which comprises:
  - (a) mixing skimmer discharge with a mixed solvent comprising a mixture of from about 90 to 50% by weight petroleum aromatic hydrocarbons having an initial boiling point in the range of from about 300-400° F. and a flash point of at least 100° F. and from about 10 to 50% by weight decyl alcohol, wherein said weights are based on the total weight of the mixed solvent; and

(b) introducing said mixture into a tank whereby a soap containing phase rises to the surface of said mixture.
